UNITED STATES PATENT OFFICE.

ALBERT E. WHITTIER, OF BRISTOL, CONNECTICUT.

OVEN-THERMOMETER.

1,003,387.

Specification of Letters Patent. Patented Sept. 12, 1911.

Application filed March 1, 1911. Serial No. 611,721.

To all whom it may concern:

Be it known that I, ALBERT E. WHITTIER, a citizen of the United States, residing at Bristol, in the county of Hartford and State 5 of Connecticut, have invented a new and useful Improvement in Oven-Thermometers, of which the following is a specification.

This invention relates to those devices which are designed to be located in openings in the walls of the ovens of wood, coal, 10 gas, oil and electric stoves and ranges, for the purpose of indicating the temperature in the interior in order that baking, roasting and other cooking may be done with 15 certainty and exactness, and with a consequent saving of time and fuel and the production of more uniformly palatable food.

The object of the invention is to provide a metallic thermometer for such purpose, 20 which is small, has few parts that are easy to form and simple to assemble, and which is very sensitive, accurate and cheap, whereby a high class article may be furnished at a low cost.

Figure 1 of the accompanying drawings shows a front view of a thermometer which embodies this invention. Fig. 2 shows a 25 plan of the back-plate and the active mechanism; the casing, pointer and dial being omitted from this view. Fig. 3 shows a section on the plane indicated by the dotted line 3—3 on Fig. 1. Fig. 4 is a view looking edgewise at the parts shown in Fig. 2.

The back-plate 1 is desirably punched 35 from thin sheet iron or steel with an ear 2 on each side. These ears are perforated for the passage of the bolts or screws which are used to secure the device in place. Fas- 40 tened to the front of the back plate at the center is a bobbin-shaped dial support which is formed of a disk 3, that is designed to be riveted or otherwise fastened to the back-plate, a stud 4 and a disk 5 to which the dial 6 is fastened by screws 7. The two disks 45 which form the ends of the dial-support are desirably placed upon reduced ends of the stud, which ends are then headed over so as to make the structure rigid. The dial may have any desired graduations, and lettering, 50 or other indications, such as the numbered segmental scale 8, for indicating the degree of heat.

Secured by rivets or other means to the back-plate is a metallic strip 9. An end of 55 this strip is turned up to provide a standard 10. One end of a thermometric arm 11

is secured to this standard. This thermometric arm is formed of two pieces of metal having different co-efficients of expansion when heated, such as copper and steel. 60 These, tightly fastened together, extend near the back-plate in a curve from the standard, around the bobbin, and terminate adjacent to the end of the strip opposite the standard. 65

A portion of the strip 9 is raised to form a bridge 12. Supported by the walls of an opening through this bridge, and by a bearing 13 secured to the back-plate, is an arbor 14. This arbor extends outward through 70 the dial, and fixed on its outer end is the pointer 15, which moves across the graduated scale on the dial for indicating the temperature in the oven. Fastened to the arbor, so as to turn it, is a lever 16. The inner end 75 of this lever extends beneath the bridge and is adapted to engage the inner surfaces of the side walls thereof. One end of a link 17 is pivoted to the outer end of the lever, while the other end of the link is connected 80 with the free end of the thermometric arm. This actuating and indicating mechanism is protected by a casing that is formed of a cylinder 18 which has an integral flange 19 at one end, the ring and flange being desirably blanked from thin sheet steel or iron. The casing is secured in position by rivets 20 which extend through the flange and the back-plate. The glass front 21 is held in place by the cap ring 22. It is customary to insert a trimming band 23 inside 85 of the casing below the cover, for the purpose of improving the appearance. 90

The dial supporting bobbin and the bridge strip bearing the thermometric arm, lever, 95 arbor and link which connects the lever with the arm, are secured to the back-plate and the arm adjusted. The dial is then fastened in position, and after the pointer is fixed on the arbor, the casing with the cover is 100 placed over the mechanism and secured to the back-plate.

This structure has but a single flat sheet of thin metal at the back, separating the actuating parts of the device from the oven. 105 There are very few parts, and these can be assembled before being attached to the back-plate. After the actuating parts are adjusted and the dial fastened, the casing is put in place and secured. The thermometric arm in this structure is only separated from the oven by a thin sheet of metal having 110

good heat conductivity, and consequently it is very sensitive. The few parts composing the structure are very cheap to form and easy to assemble. The thermometric arm 5 can be attached to the bridge strip, and, through the link and lever, to the spindle before the bridge strip is secured in place. All of the adjustments may be made before the casing is placed in position.

10 In practice it has been found that this very simple mechanism is exceedingly sensitive and quite accurate, both when the temperature is rising and falling in the oven of the stove or range to which it is applied.

15 The invention claimed is:

An oven thermometer having a thin sheet metal back-plate, a strip, having a portion

raised to form a bridge and one end turned up to form a standard, secured to the front of the back-plate, an arbor supported by the back-plate and the bridge, a lever secured to said arbor, a thermometric arm with one end secured to the standard, a link connecting the other end of the thermometric arm and the lever, a bobbin secured to the front of the back-plate, a dial fastened to said bobbin, a pointer fixed to the arbor and movable across the dial, and a casing secured to the back-plate over the aforesaid actuating and indicating parts.

ALBERT E. WHITTIER.
